UNITED STATES PATENT OFFICE.

MENDEL PIANKO, OF CHICAGO, ILLINOIS.

METHOD OF PRODUCING DENTAL PLATES.

No Drawing.

Application filed October 6, 1921. Serial No. 505,957.

To all whom it may concern:

Be it known that I, MENDEL PIANKO, a citizen of the United States, residing at Chicago, in the county of Cook and State of Illinois, have invented a new and useful 5 Method of Producing Dental Plates, of which the following is a specification.

This invention relates to a method of preparing dental plates whereby a very accurate, 10 thin and light all metal plate can be produced directly from the plaster impression without going through the intermediate steps now necessary before the usual type of rubber or other form of plate can be produced. It is a well known fact that owing 15 to the necessary expansion and shrinkage from the heating and cooling of the plate during the formation thereof the plate will ofttimes become distorted so that it will not 20 fit the mouth as accurately as desired or conform strictly with the configuration of the plastic cast or impression. It is an object of the present invention to provide a method 25 of producing plates which will preserve the exact contour of the plastic impression, which obviates the necessity of distorting the plate through the action of heat, and which overcomes the discomforts and inconveniences due to the use of thick and heavy 30 plates.

With the foregoing and other objects in view the invention consists in certain novel steps in the method hereinafter more fully described and pointed out in the claim, it 35 being understood that various changes may be made in the method without departing from the spirit of the invention as claimed.

When it is desired to prepare a plate a negative impression of the mouth is taken 40 as ordinarily. This impression is coated with a shellac solution on which is formed

another cast which is a positive of the impression, this positive being made before the impression has had a chance to shrink. This second impression is then dusted thoroughly 45 with finely pulverized metal such as graphite. The impression thus treated is then suspended from the negative pole of a battery containing a solution of the metal of which the plate is to be formed and a plate 50 of the same metal is hung from the positive pole. An electric current is then directed through the solution from the positive to the negative pole with the result that the metal will be deposited on the graphite coating of the impression and an accurate plate 55 will be produced conforming in every detail to the configuration of the mouth. After the plate has thus been produced the teeth can be assembled with the plate by means 60 of vulcanite or rubber and the rubber vulcanized onto the metal.

What is claimed is:—

The herein described method of producing a dental plate which consists in taking an 65 impression of the mouth, coating the impression, while wet, with a shellac solution, making a positive from the shellacked surface of the impression, applying a coating of graphite or other suitable metal to the second 70 impression, suspending the second impression while wet from the negative pole of an electroplating apparatus, and setting up an electrical current through the apparatus to plate the impression with a desired 75 metal.

In testimony that I claim the foregoing as my own, I have hereto affixed my signature in the presence of a witness.

MENDEL PIANKO.

Witness:

Ivy E. SIMPSON.
